CLAIM

The ornamental design for a bolt, as shown and described.

DESCRIPTION

FIG. 1 is a perspective view of my new design showing a bolt;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a section cut view taken along VIII-VIII of FIG. 6.
